US00D788255S

(12) **United States Design Patent** (10) Patent No.: **US D788,255 S**
(45) Date of Patent: **** May 30, 2017**

(54) **REMOTELY CONTROLLED TIP UP ASSEMBLY**

(71) Applicant: **Theodore A. Rayfield**, Hayward, WI (US)

(72) Inventor: **Theodore A. Rayfield**, Hayward, WI (US)

(**) Term: **14 Years**

(21) Appl. No.: **29/513,644**

(22) Filed: **Jan. 4, 2015**

(51) LOC (10) Cl. **22-05**

(52) U.S. Cl.

USPC **D22/137**

(58) **Field of Classification Search**

USPC **D22/137**

CPC **A01K 7/01; A01K 7/02**

See application file for complete search history.

(57) **CLAIM**

The ornamental design for a remotely controlled tip up assembly, as shown and described.

DESCRIPTION

FIG. 1 is a front view of the remotely controlled tip up assembly embodying my new design, with the signal shaft and spool shaft in operating position,

FIG. 2 is a rear view thereof,

FIG. 3 is a left side view thereof,

FIG. 4 is a right side view thereof,

FIG. 5 is a top view thereof,

FIG. 6 is a bottom view thereof,

FIG. 7 is a perspective front view of the remotely controlled tip up assembly of the present invention,

FIG. 8 is a perspective front view of the remotely controlled tip up assembly of the present invention with the signal staff and spool shaft in storage position; and,

FIG. 9 is a bottom view of the remotely controlled tip up assembly of FIG. 8.
